UNITED STATES PATENT OFFICE.

CHARLES H. SHEPARD, OF BROOKLYN, NEW YORK, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 727,001, dated May 5, 1903.

Application filed February 12, 1900. Serial No. 4,847. (No model.)

To all whom it may concern:

Be it known that I, CHARLES H. SHEPARD, a citizen of the United States, and a resident of the borough of Brooklyn, city of New York, 5 in the county of Kings and State of New York, have invented certain new and useful Improvements in Type-Writing Machines, of which the following is a specification.

The present invention relates to an escapement mechanism for type-writing and other machines, and has for one object the provision of means whereby the machine is adapted for the use of operators of all kinds—that is, those who manipulate the keys at speeds 15 ranging from high to low—the means being of such character that the spacing mechanism as a whole automatically accommodates itself to the varying speed of the user or users.

In escapement mechanisms heretofore used 20 for governing the letter-space movement of the carriage there has been provided a rack (straight or segmental or circular) which the dogs are adapted to alternately engage. One of these dogs is normally in engagement with 25 the rack and the other is normally disengaged therefrom, and upon the actuation of a type-operating key the first dog is withdrawn from and the second dog is brought into engagement with the rack. In order that the 30 first dog may be disengaged from the rack, so as to move forward one tooth thereof, it is necessary that the second dog be engaged with the rack to a considerable or undue extent or width, and as a result of such undue 35 extent of engagement between the second dog and the rack a considerable interval of time must elapse between the release of the depressed key and the disengagement of the said second dog from the rack, during all of 40 which time the carriage is held stationary, or, in other words, the carriage is unduly delayed in beginning its letter-spacing movements, thus causing letters to be printed on or overlapping each other or to be irregularly spaced at the rapid operation of the 45 keys. To remedy this difficulty, an escapement mechanism has been designed which comprises a holding-dog having two faces at an angle to each other—that is to say, the 50 dog is beveled at the escape edge thereof

and the rack-tooth passes from the straight to the beveled face of the dog immediately upon the release of the key; but this construction is, nevertheless, objectionable, for the reason that if the key is not depressed with 55 sufficient rapidity the escapement-wheel begins to move during the key depression, and the tooth thereof strikes upon the bevel-face of the dog, in consequence of which an objectionable camming action occurs which unfits 60 the escapement for the use of those operators who do not manipulate the keys with sufficient speed to cause the straight face of the holding-dog to jump into engagement with the escapement-teeth. 65

As above stated, one object of the present invention is to secure that one and the same escapement mechanism shall answer for all classes of operators and to secure that the written letters shall always be properly 70 spaced. Other objects in relation thereto will hereinafter appear.

A further object is to provide means for locking the keys at the completion of the line of writing. 75

To these ends my invention consists in certain features of construction and combinations of devices hereinafter more fully described, and particularly pointed out in the 80 appended claims.

The preferred form of the invention is illustrated in the accompanying drawings, forming part of this specification, in which—

Figure 1 is a central vertical longitudinal sectional view of a type-writing machine embodying the invention. Fig. 2 is a rear elevation of the upper part of the machine shown in Fig. 1, with the framework partly broken away and in section and showing the carriage-escapement mechanism in normal position. Fig. 3 is a fragmentary plan view of the rear part of the machine shown in Fig. 1. Fig. 4 is a diagrammatic rear elevation, partly in section, illustrative of the operation of the escapement when the key is depressed slowly 85 or with a legato touch. Fig. 5 is a similar view illustrative of the operation when a key is depressed quickly or with a staccato touch and in which the release of the carriage for letter-spacing occurs before the impact of the 90 95 100

type. Fig. 6 is a detail plan view illustrative of a key-locking action. Fig. 7 is a detail view, partly in section, upon the line X X of Fig. 6. Fig. 8 is a detail view in section 5 upon the line Y Y of Fig. 4. Fig. 9 is a perspective view of a stepping or feeding dog shown in Figs. 1, 2, 3, 4, and 5. Fig. 10 is a detail perspective view of a dog-operating lever shown in Figs. 2, 4, and 5. Fig. 11 is a 10 detail perspective view of an abutment shown in Figs. 1 and 3 and indicated in Figs. 2, 4, and 5. Fig. 12 is a view similar to Fig. 8, but showing a modification of the dog-locking device. Fig. 13 is a similar view to Fig. 15 12, but showing the parts in normal position. Fig. 14 is a perspective view of the escapement-lever and dog-locking device shown at Fig. 13.

In some of the views parts of the machine 20 are omitted for the sake of clearness.

The same character of reference is used in the various views of the drawings to designate the same part.

1 is a base-frame; 2, uprights or standards 25 thereon; 3, a top plate or type-ring secured to the standards 2; 4, one of a series of type-bar hangers attached to the ring 3; 5, type-bars journaled in the hangers 4; 6, types borne by the bars 5; 7, a rod pivotally connected with the type-bar 5; 8, key-levers pivotally connected with the rods 7 and provided with keys 9 at their forward ends and also with notches 10 in their upper edges at their rear ends; 11, a rib integral with base 30 1, forming a fulcrum for the levers 8; 12, springs attached to a cross-bar 13 and holding the key-levers in engagement with the rib 11; 14, space-key levers also fulcrumed upon the rib 11; 15, a universal bar underlying the type-key levers and space-key levers; 16, one of a pair of vertical rods connected with the universal bar 15 at its ends and hooking over a transverse bar 17; 18, a rock-shaft journaled in lugs of a downwardly- 40 45 extending plate or frame 19, attached to the top plate 3; 20, an arm extending forwardly from the rock-shaft 18 and bearing a transverse bar 17; 21, a spring hooking at one end over a bar of the frame 19 and attached 50 at its other end to a collar 22, adjustable around the shaft 18 in a well-known manner; 23, rails borne by upstanding ears or lugs of the top plate 3; 24, a carriage running upon and guided by the rails 23; 25, a spring- 55 60 drum connected with the framework of the machine; 26, a strap connecting the drum with an arm 27, attached to the carriage 24; 28, a platen-carrier connected with the carriage 24 in a known manner; 29, a platen journaled in the carrier 28; 30, a supporting-roll at the forward side of the carrier 28 and running upon a shift-rail 31; 32, a rack pivotally connected with the carriage by arms 33; 34, a pinion with which the rack 32 engages; 35, a shaft 65 upon which the pinion 34 is fast; 36, a bearing for the shaft 35; 37, a circular rack or ratchet-

70 wheel connected with the shaft 35 in any suitable manner, as by a backing-ratchet within a casing 38; 39, a graduated rack-bar pivotally mounted upon the framework of the machine, so as rock and also to move endwise a limited distance; 40, a compression-spring for holding the bar 39 toward the right-hand side of the machine; 41 and 42, left and right hand margin-regulators adjustable upon the 75 bar 39; 43, an adjustable margin-stop for the left-hand side of the paper, adapted to be released from engagement with a coacting part (not shown) on the carriage by the rocking of the bar 39; 44, an adjustable right-hand 80 margin-stop adapted to coact with a trip 45 upon the carriage to turn the bar 39 so as to raise a bell-hammer 39^a, fixed on said bar, and then to release said bar so that said hammer may fall and strike a bell 39^b, and 46 an arm 85 on the bar 39, which is engaged by an arm 47 of a release-rod 48, by means of which the bar 39 may be rocked at will.

The foregoing devices are substantially of the construction to be found in the well-known 90 Remington No. 6 machine.

In that form of the present invention illustrated in the drawings the rock-shaft 18 is provided with a rearwardly-extending arm 49, to the end of which is pivotally connected the 95 lower end of a vertical two-part rod 50, having a turnbuckle 51. The upper end of the rod 50 is pivotally connected to an escapement lever or rocker 52, which is pivoted upon a shoulder-screw 53, attached to a horizontal 100 stud 54, extending back from the plate 19. The escapement-rocker 52 is formed with three arms, one of which is shaped to form a detent-dog 55 for engagement with the teeth of the rack 37. Another arm 56 thereof is 105 adapted to coact with padded stops 57 and 58 to limit the motion of the lever in each direction. The padded stop 57 is shown as integral with a bracket 59, which is attached to the rear face of the frame 19 by means of a 110 slot 60 and a screw 61, whereby provision is made for the vertical adjustment of the bracket and stop. Pad-stop 58 is attached to a vertical screw 62, which engages with a threaded hole in an arm 63 in the bracket 59 115 and is provided with a locking-nut 64 for holding it in any adjusted position. A third arm 65 of the escapement-rocker is bent over at 66 to form a ledge whereon is provided an adjustable screw-stop 67 for a dog 68, which 120 is pivoted at 69 to the lever-arm 65. Said dog is provided with an arm 70, extending along the arm 65 toward the pivot 53. A spring 71, attached to the arm 65, bears against the arm 70 and is tensioned to press the dog 125 68 against the stop 67. The end of the arm 70 is provided with a circular or a disk-shaped enlargement 72, which is adapted to fit between the prongs of the forked portion of a lever 73, pivoted at 74 to the escapement-lever 52. One arm of the fork of the lever 73 is extended, as at 75, in a direction substan-

tially at a right angle to the direction of the lever 73, and near its free end the branch 75 is provided with a lateral pin 76.

Attached to the vertical plate 19 is a hollow air-check cylinder 76, open at its lower end and closed at its upper end 77. Within the cylinder is a piston or check 78, provided with a rod 79, extending through a perforation in the head 77. The end of the rod is enlarged and provided with a transverse slot 80 to engage the pin 76 on the said branch 75 of the lever 73. Adjacent the head 77 is the cylinder, provided with a vent 81, connecting with the inside or hollow of the cylinder 76. The area of the vent 81 may be varied by an adjustable screw 82, which engages with a threaded hole in the metal through which the vent passes and closes the vent to a greater or lesser degree according to the adjustment. I provide the dog 68 with a thin sharp lateral projection 83 and attach to the top plate 3 a blade 84, preferably formed integral with its supporting-bracket 85, which is provided with a slot 86 for the passage of a screw 87, by which it is adjustably secured upon the top plate 3.

The operation of the above-described escapement will be described first in connection with Fig. 4, which is intended to illustrate the "natural feed" or, in other words, the action of the parts when a legato blow or stroke is made upon a key and the carriage is released during the return of the finger-key to normal position. Upon the depression of a finger-key the universal bar 15 and arm 20 are moved downwardly and the arm 49 and rod 50 are raised, thus rocking the dog-carrier 52 toward the right in Fig. 2. The dog 68 is carried upward and to the right in Fig. 2 and in front of the working face of the adjacent rack-tooth *a*, as illustrated in Fig. 4, and at the same time the detent-dog 55 is moved out of engagement with the working face of a rack-tooth *e*, Fig. 4 illustrating the positions of the parts at the instant before the tooth *e* is released by the dog 55, which release occurs upon a slight further movement of the rocker toward the right. During the described operation the air-check piston 55 has a normal movement from the dotted-line to the full-line position shown at Fig. 4, the tension of the spring 71 being sufficient to overcome the resistance of the air when passing slowly through the vent 81 and hold the parts 73 and 68 in their normal positions relatively to the moving escapement-lever 65. Upon the release of the tooth *e* by the dog 55 the rack 37 turns forward or "drops" a slight distance until the point of the tooth *a* engages with the face of the dog 68. Upon the release of the depressed key after the impact of the type the parts are returned to normal positions by the springs 12 and 21, thus moving the dog 68 from in front of the tooth *a* and moving the dog 55 in behind the back of the tooth *e* and in front of the tooth *f* of the wheel 37, which is rotated by the car-

riage-driving spring upon the tooth *a* being released by the dog 68 and until the tooth *f* is arrested by the dog 55. This brings the tooth *b* into the position occupied by the tooth *a* in Fig. 4 or adjacent the dog 68, so that the paper-carriage is advanced one letter-space.

The action of the parts when automatically operating as a speed or "reverse-feed" escapement will next be described in connection with Figs. 2 and 5. Upon the depression of a key by a quick or staccato stroke the rocker 52 is quickly thrown to the right in Fig. 2 and the piston 78 and lever 73 are checked by the confined air, thus causing the dog 68 to swing independently upon its pivot 69 from the position shown in Fig. 2 to one in which the projection 83 thereon passes beneath the blade 84—that is, one in which the blade 84 is between the projection 83 and the stop 67. This independent movement swings the point of the dog 68 to the right of the point of tooth *a* and in position to arrest the ratchet-wheel 37 by contact with the next tooth *b* thereof as soon as the tooth *e* is released by the still moving dog 55, which release occurs just before the impact of the type upon the platen; but in advancing from the position shown in Fig. 5 until arrested by the dog 68 the rack-tooth *b* does not move at once to the position just occupied by the rack-tooth *a*, inasmuch as the dog 68 when struck by rack-tooth *b* is prevented from contacting with the stop 67, owing to the engagement of projection 83 on the dog with the fixed blade 84. Upon the subsequent relief of the depressed finger-key from pressure the parts are returned to normal positions by their springs, and during such return the detent-dog 55 moves in front of the working face of the tooth *f* before the dog 68 is released from the control of the blade 84, and hence is in position to catch and hold the tooth *f* as soon as the dog 68 is released upon the disengagement of the projection 83 from blade 84. By providing a sufficient amount of drop for the tooth normally adjacent to the dog 68 it is secured that the dog 55, which is shown as being rigid with the rocker or carrier 52, will surely pass behind the tooth it releases, and a more inexpensive construction is secured than would be the case were the dog 55 arranged to have a limited throw independently of its carrier to move it into position behind the tooth from which it is disengaged and no drop be provided for.

Referring now to Figs. 12, 13, and 14, it will be observed that the detent or lock 84 and the lateral dog-tooth 83 are omitted and that the dog 68 is provided with a projection 68^a and that a catch-lever 68^b of the first order is pivoted at 68^c to the escapement-lever 52. The catch-lever is provided with a notched end to engage the projection 68^a and also with an operating-spring 68^d, the latter being secured to the escapement-lever 52 and bearing upon the other arm of said catch-

lever. Whenever the dog 68 is independently turned upon its pivot, the said spring causes the catch to snap into engagement with the projection 68^a, so that the dog 68 is enabled to arrest the escapement-wheel 37 before the advance movement of the latter is completed and to hold said wheel while the dog 55 is returning to normal position, so that the latter is enabled to engage the tooth next to the one that it released in its withdrawing motion. Upon the return of the escapement-lever to normal position the spring-pressed arm of the catch-lever 68^b is intercepted and arrested by an adjustable screw-stop 68^c, mounted in a bracket 68^f, secured to the vertical plate 19 in a similar manner to bracket 59. As the escapement-lever completes its return movement the catch-lever turns independently upon its pivot and releases the dog 68, which at once vibrates to normal position under the tension of the spring 71. It will thus be seen that at the rapid operation of a finger-key the check 78 has an abnormal movement or a movement not so great as when the parts are operated slowly and that by reason of such abnormal movement the dog 68 is caused to move to an abnormal position behind the rack-tooth *a*, so that upon the separation of the detent-dog 55 from the rack-tooth *e* during the movement of the type to the platen the carriage is released, so that it can practically complete a letter-spacing movement independently of the return of the escapement-dogs to their initial position. Hence the checking devices operate to determine during the initial movement of the finger-key, universal bar, and connections upon which side of the rack-tooth the dog 68 shall enter, and therefore to determine whether the feeding movement of the carriage shall be "natural" or "reverse," and such determination is made automatically before the normally disengaged dog 68 enters the path of the escapement or rack teeth and also before the normally engaged dog 55 becomes disengaged from the rack-tooth. It will also be observed that if the screw 82 should be turned in enough to nearly or entirely close the vent 81 the mechanism would always operate as a reverse feed, or, on the other hand, if the screw 82 should be removed the mechanism would always operate to produce the natural feed, it being understood that the vent 81 is sufficiently large to permit the natural operation of the feeding mechanism when the screw 82 is withdrawn from the vent. It will be further noted that by adjustment of the screw 82 the mechanism can be caused to operate as the reverse feed when the keys are operated at only average speed, or, if desired, it may be adjusted so as to open the vent, so that the mechanism will operate to produce the natural feed at all times, except when the very highest speed of operation is attained. For operators who strike the keys a quick blow, but do not recover the stroke, or, in other words, do not

release the keys with corresponding celerity, the latter adjustment is preferable; but for operators who release the keys promptly at all times the former adjustment is preferable. Again, in the case of operators who are able to release the keys promptly when writing upon single sheets, but who find it difficult to remove the fingers promptly from the keys after striking heavy blows thereon, as in manifolding, the improvement is especially desirable, because the screw 82 can be adjusted from time to time to suit the requirements of the work on hand—that is, the area of the vent may be reduced when single copies are being produced and may be increased when the machine is used for manifolding. Thus by simple adjustment of a single screw the same machine can be adapted either for slow operators, who require the natural feed, or for expert operators, who can advantageously employ the reverse feed at all times and in doing all classes of work, or for rapid operators, who can occasionally employ the reverse feed to advantage, but at other times require the natural feed. An operator of the class last mentioned upon discovering the carriage movement not to be sufficiently prompt to meet his speed of operation could turn the screw 82 so as to reduce the vent, or at other times in doing tabular or manifolding work or any character of work requiring a slower or more careful operation of the machine than usual or in case he should be too fatigued to operate the keys with rapid and precise movement he could enlarge the vent, so that the mechanism would produce only the natural feed. Other operators would doubtless find it possible to make such an adjustment of the vent as would enable the machine to meet all their requirements, automatically giving the natural feed for work requiring more than usual care and precision and the reverse feed where speed of operation is the principal object sought. Thus the mechanism operates as reverse feed or natural-feed according as the speed of the operation of the finger-keys is above or below a predetermined rate or standard, an adjustable device being provided for determining at what rate of speed the operation of the escapement mechanism shall change from natural to reverse and either making the rate or standard so low that it would be impossible to obtain a natural-feed movement or making the standard so high that it would be impossible to obtain a reverse-feed movement of the carriage or adjusting the standard at any point between these two extremes. In other words, the device may be adjusted for natural feed at all speeds or for reverse feed at all speeds or for an automatically "convertible feed," so that it will cause natural or reverse feed of the carriage according to the speed of operation of the keys.

The line-locking mechanism will now be described. A hook comprising an arm 88 and a tooth 89 is pivoted at 90 upon a bracket or

arm 91, fastened upon the top plate 3 by means of a screw 92. The said tooth 89 lies adjacent to a notch 89^a, formed in the arm 65 of the escapement-lever, but normally out of 5 the path of movement of the escapement-lever. A spring 93, connected at one end to the said hook and at the other end bearing upon the bracket 91, is tensioned to swing the arm 88 forwardly away from the escapement- 10 lever. The movement of the arm 88 is limited by two lugs 94, formed thereon and forking a vertical pin 95, fixed in said bracket 91. Sufficient play is allowed by the lugs 94 to permit the tooth 89 to move into the 15 notch 89^a. The bar 39 is provided with a pin 96, depending from its under side, and the arm 88 is provided with a spring-finger 97, the latter being fixed to said arm at 97^a. The pin 96 is adapted to engage with the spring 20 97 at the endwise movement of said bar 39. This movement of the bar occurs when the paper-carriage 24 has advanced sufficiently far in letter-space direction to enable the trip-piece 45 to engage a lug 98, formed upon 25 the adjustable stop 44, arranged upon said bar 39, it being understood that by means of said engagement the carriage is enabled to move the stop 44, together with the bar, in endwise direction and that said movement 30 compresses the spring 40. During this movement of the bar the pin 96 moves the spring-finger 97, and consequently the hook, about said pivot 90, causing the tooth 89 to move into the notch 89^a of the escapement-lever, 35 and so lock the latter against movement. The finger 97 is made yielding, so that if the point of the tooth 89 should contact with the rear vertical face of the lever-arm 65 while the latter is in working position and be 40 thereby arrested the movement of the bar 39 and the paper-carriage may nevertheless continue, as the said finger 97 yields sufficiently for this purpose, and as soon thereafter as the escapement-lever returns to normal position 45 the hook 89 snaps into the notch 89^a under the tension of the spring 97. The position of the parts at this time is illustrated at Fig. 6. By thus locking the escapement-lever further movement is prevented of the 50 connection 50, arm 49, rocking frame 20, links 16, universal bar 15, and key-levers 8, thus notifying the operator that the end of the line has been reached. Should it be desired to write a few more letters to complete a 55 word, the rod 48 may be moved rearwardly, as usual, so as to rock the bar 39 upon its pivots and disengage the trip 45 from the lug 98, so that spring 40 may return the bar 39 endwise to normal position. The pin 96 60 upon said bar thus liberates the spring-finger 97, so that the tooth 89 is withdrawn from the notch 89^a by means of the spring 93, and further movement of the escapement-lever, and hence of the finger-keys, is permitted, so 65 that the machine may be operated until the trip 45 strikes a pin 99, fixed upon the adjustable sleeve 42 on said bar 39, causing a

second and final movement of the bar 39 to locking position.

As the mechanism herein set forth includes 70 many features which are broadly new, I do not wish it to be considered that the invention is limited to the precise details of construction and arrangement given, since many changes may be made without departing 75 from the invention. Some parts of the invention may be used without others. While I have shown the same as applied to a Remington No. 6 type-writing machine, it will of course be understood that it is applicable to 80 type-writing machines of other construction.

What I claim as new, and desire to secure by Letters Patent, is as follows:

1. In a type-writing machine, the combination with a carriage and an escapement-rack 85 therefor, of a reciprocatory escapement-dog mechanism, including a part which may be positioned automatically during the initial movement of the escapement-dog mechanism, so as to cause either a natural or reverse 90 feed of the carriage, according to the speed of operation.

2. In a type-writing machine, the combination of a series of type-operating keys, a universal bar operated by said keys, a carriage, 95 an escapement-rack for said carriage, and a reciprocatory escapement-dog mechanism operatively connected to said universal bar and including a part which may be positioned automatically during the initial movement 100 of the universal bar, so as to cause either a natural or reverse feed of the carriage, according to the speed of operation.

3. In a type-writing machine and in an escapement mechanism, the combination with 105 a carriage of an escapement-rack therefor, a dog normally engaging said rack, and a dog normally disengaged from the rack but constructed to enter the path of the rack-teeth as the first-mentioned dog is withdrawn therefrom, said normally disengaged dog being constructed to enter said path either in advance of or behind the rack-tooth adjacent thereto.

4. In a type-writing machine, the combination with a carriage, of a key-controlled adjustable escapement mechanism and means for affording either a natural feed at all speeds or a reverse feed at all speeds, or a feed in which the carriage is released either 120 before or during the release of the key, according to the speed of operation.

5. In a type-writing machine and in an escapement mechanism, the combination with 125 a carriage of an escapement-rack and suitable coacting escapement elements, the construction and arrangement being such that the escapement mechanism may operate either as a "natural feed" or as a "reverse feed," and an air-check for determining in which of 130 said ways the escapement mechanism shall operate.

6. In a type-writing machine, the combination with a series of type-operating keys and

a universal bar operated thereby, of a carriage, a rack, and an escapement-dog mechanism connected to said universal bar, said escapement-dog mechanism including both 5 means for releasing the carriage during either the initial or return stroke of the universal bar, and also means for determining automatically during which stroke of the universal bar the carriage shall be released, according to the speed of operation of the keys.

7. In a type-writing machine and in an escapement mechanism, the combination with a carriage of an escapement-wheel therefor, having pointed teeth, a pivoted escapement-lever having pointed teeth or dogs, one of which is normally in engagement with said escapement-wheel, and the other of which is normally disengaged therefrom, the axis of said lever being in a plane parallel with the 15 thin edges of said pointed escapement-wheel teeth, so that said dogs work substantially in the directions in which the adjacent wheel-teeth point, and the construction and arrangement being such that upon the withdrawal of said normally engaged dog said normally disengaged dog enters the wheel just behind the adjacent wheel-tooth, and such that the carriage is thereby enabled to practically complete a letter-spacing movement 20 independently of the return movement of the escapement-dogs.

8. In a type-writing machine and in an escapement mechanism, the combination with a carriage, of an escapement mechanism automatically acting as a natural or reverse feed escapement according as the speed of operation is above or below a given rate, and an adjustable device for determining at what 25 rate of speed the escapement mechanism shall operate as a reverse feed.

9. In a type-writing machine and in an escapement, the combination of a rack, a holding-dog normally disengaged therefrom, and means for automatically adjusting the position 30 of said holding-dog relative to the rack-teeth to cause natural or reverse feed letter-space movement according as the speed of operation is above or below a given rate.

10. In a type-writing machine and in an escapement, the combination of a rack, a holding-dog normally disengaged therefrom, means for automatically adjusting the position 35 of said holding-dog relative to the rack-teeth to cause natural or reverse feed letter-space movement according as the speed of operation is above or below a given rate, and an adjustable device for determining at what rate of speed the escapement mechanism shall operate as a reverse feed.

11. In a type-writing machine and in an escapement, the combination of a rack, a dog normally disengaged therefrom and movable in or parallel to the plane thereof, means for holding the dog normally in position to engage 40 with the front or working face of the adjacent rack-tooth on the actuation of a key,

and means for moving said dog into position in rear of said tooth whenever the speed of operation exceeds a given rate, whereby the letter-space feed movement is natural or reverse according as said operative speed is less or greater than a given rate. 70

12. In a type-writing machine and in an escapement, the combination of a rack, a dog normally disengaged therefrom and movable in or parallel to the plane thereof, means for holding the dog normally in position to engage with the front or working face of the adjacent rack-tooth, means for moving said dog into position in rear of said tooth whenever the speed of operation exceeds a given rate, whereby the letter-space feed movement is natural or reverse according as said operative speed is less or greater than a given rate, and an adjustable device for determining at 80 what rate of speed the escapement mechanism shall operate as a reverse feed. 85

13. In a type-writing machine and in an escapement mechanism, the combination of a rack, a dog normally disengaged therefrom, a dog-carrier on which the dog is movable independently in or parallel to the plane of the rack, a stop against which the dog is spring-held in position to engage with the front or working face of the adjacent rack-tooth, and means for moving said dog away from said stop and into position in rear of said adjacent tooth whenever the speed of operation exceeds a given rate, whereby the letter-space movement is natural or reverse according as 90 said operative speed is less or greater than the given rate. 95

14. In a type-writing machine and in an escapement mechanism, the combination of a rack, a dog normally disengaged therefrom, a dog-carrier on which the dog is movable independently in or parallel to the plane of the rack, a stop against which the dog is spring-held in position to engage with the front or working face of the adjacent rack-tooth, means for moving said dog away from said stop and into position in rear of said adjacent tooth whenever the speed of operation exceeds a given rate, whereby the letter-space movement is natural or reverse feed according as said operative speed is less or greater than the given rate, and an adjustable device for determining at what rate of speed the escapement mechanism shall operate as a reverse feed. 105 110 115

15. In a type-writing machine and in an escapement mechanism, the combination of a rack, a rocker, a dog movable on said rocker, and normally disengaged from the rack, a stop against which the dog is normally spring-held in position to engage with the front or working face of the adjacent rack-tooth, a lever engaging with the dog, and means for actuating said lever and dog to move the latter into position to pass in rear of said adjacent tooth whenever the speed of operation exceeds a given rate, whereby the letter-space 120 125 130

feed movement is natural or reverse according as said operative speed is less or greater than a given rate.

16. In a type-writing machine and in an escapement mechanism, the combination of a rack, a rocker, a dog movable on said rocker and normally disengaged from the rack, a stop against which the dog is normally spring-held in position to engage with the front or working face of the adjacent rack-tooth, a lever engaging with the dog, means for actuating said lever and dog to move the latter into position to pass in rear of said adjacent tooth whenever the speed of operation exceeds a given rate, whereby the letter-space feed movement is natural or reverse according as said operative speed is less or greater than a given rate, and an adjustable device for determining at what rate of speed the escapement mechanism shall operate as a reverse feed.

17. In a type-writing machine and in an escapement mechanism, the combination of a rack, a rocker, a dog arranged upon and movable relatively to said rocker and normally disengaged from the rack, a stop against which the dog is spring-held, and an air-check connected with the dog and operating to move the same into position in rear of the adjacent rack-tooth and away from said stop whenever the speed of operation exceeds a given rate and thereby to change the escapement from natural to reverse feed.

18. In a type-writing machine and in an escapement mechanism, the combination of a rack, a rocker, a dog arranged upon and movable relatively to said rocker and normally disengaged from the rack, a stop against which the dog is spring-held, an air-check connected with the dog and operating to move the same into position in rear of the adjacent rack-tooth and away from said stop whenever the speed of operation exceeds a given rate and thereby changing the escapement from natural to reverse, and an adjustable device for determining at what rate of speed the escapement mechanism shall operate as a reverse feed.

19. In a type-writing machine and in an escapement mechanism, the combination of a rack, a rocker, a dog pivoted to said rocker and normally disengaged from the rack, a stop against which the dog is normally spring-held in position to engage with the front or working face of the adjacent rack-tooth, a lever pivoted to said rocker and connected to said dog, a cylinder having a vent, and a piston arranged in said cylinder and connected to said lever, the whole being arranged to cause the movement of said dog away from said stop and into position in rear of said adjacent rack-tooth whenever the speed of operation exceeds a given rate and thereby to change the escapement from natural to reverse feed.

20. In a type-writing machine and in an es-

capement mechanism, the combination of a rack, a rocker, a dog pivoted to said rocker and normally disengaged from the rack, a stop against which the dog is normally spring-held in position to engage with the front or working face of the adjacent rack-tooth, a lever pivoted to said rocker and connected to said dog, a cylinder having a vent, a piston arranged in said cylinder and connected with said lever, the whole being arranged to cause the movement of said dog away from said stop and into position in rear of said adjacent tooth whenever the speed of operation exceeds a given rate, and thereby to change the escapement from natural to reverse, and an element adjustable to vary the size of said vent.

21. In a type-writing machine, the combination of a carriage, type mechanism, a ratchet-wheel connected with the carriage, a rocker vibrating in or parallel to the plane of said ratchet-wheel and provided with escapement-dogs and operatively connected with the type mechanism, an arm normally disengaged from said rocker, and a yielding device, as 97, moved by the carriage, for engaging said arm with said rocker when the carriage has reached a predetermined point to lock the rocker and type mechanism against motion. 95

22. In a type-writing machine and in an escapement mechanism, the combination of a rack, a dog normally disengaged therefrom and adapted to be moved in front of the adjacent rack-tooth and movable independently 100 parallel with the rack, means for shifting or moving the dog independently into position to pass behind said tooth whenever the dog is moved toward the rack at or above a given rate of speed, and a detent device for holding said dog in said shifted position while engaged with the rack.

23. In a type-writing machine and in an escapement mechanism, the combination of a rack, a dog normally disengaged therefrom 110 and adapted to be moved in front of the adjacent rack-tooth and movable independently parallel with the rack, and means for shifting or moving the dog independently into position to pass behind said tooth whenever the 115 dog is moved toward the rack at or above a given rate of speed.

24. In a type-writing machine and in an escapement mechanism, the combination with a carriage and an escapement-rack therefor, 120 of escapement-dogs constructed to cause either a natural or reverse feed of the carriage and an air-check so connected to said escapement-dogs as to determine automatically which kind of feed shall take place according to the speed of the key-strokes. 125

25. In a type-writing machine and in an escapement mechanism, the combination with a carriage and an escapement-rack therefor, 130 of escapement-dogs constructed to cause either a natural or reverse feed of the carriage, and an adjustable air-check so con-

nected to said escapement-dogs as to determine automatically which kind of feed shall take place according to the speed of the key-strokes, the construction and arrangement 5 being such that by adjusting said air-check, the rate of speed necessary to secure the reverse feed may be varied.

26. In a type-writing machine and in an escapement mechanism, the combination with 10 a carriage-rack, of a dog adapted to assume a position to effect either a natural or reverse feed, a spring for holding said dog automatically in position to secure a natural feed, means for moving said dog to a position to 15 secure the reverse feed, and a check for holding said dog in the last-mentioned position.

27. In a type-writing machine and in an escapement mechanism, the combination with 20 a carriage-rack, of a rocker, a dog pivoted thereon, a spring for holding said dog in a position to secure a natural feed of the carriage, means for moving said dog automatically to a position for securing a reverse feed 25 of the carriage, and a spring-pressed check pivoted on said rocker and adapted to engage

said dog to hold it in the last-mentioned position.

28. In a type-writing machine and in an escapement mechanism, the combination with 10 a carriage-rack, of a rocker, a dog pivoted thereon, a spring for holding said dog in a position to secure a natural feed of the carriage, means for moving said dog to a position for securing a reverse feed of the carriage, a spring-pressed check pivoted on said 35 rocker and adapted to engage said dog to hold it in the last-mentioned position, and means for automatically releasing said check upon the return of said rocker to normal position, so that said dog may resume the natural-feed 40 position.

Signed in the borough of Manhattan, city of New York, in the county of New York and State of New York, this 10th day of February, A. D. 1900.

CHARLES H. SHEPARD.
